UNITED STATES PATENT OFFICE.

CHARLES H. METZ, OF WALTHAM, MASSACHUSETTS.

DESIGN FOR A GEAR-CASE MEMBER.

SPECIFICATION forming part of Design No. 30,410, dated March 28, 1899.

Application filed March 2, 1899. Serial No. 707,558. Term of patent 7 years.

To all whom it may concern:

Be it known that I, CHARLES H. METZ, of Waltham, in the county of Middlesex and State of Massachusetts, have invented and 5 produced a new and original Design for a Gear-Case Member, of which the following is a specification, reference being had to the accompanying drawings, forming part thereof.

In the drawings, Figure 1 represents a perspective view of a gear-case member, illustrating my new design. Fig. 2 represents a sectional view of the same, taken on a line *a a*, Fig. 1.

The leading features of my new design for 15 a gear-case member consist in the design as herein shown and described.

As shown in the drawings, the cap 5 has the convex top 6 with the central opening 7, the

annular wall of the cap being continuous at its edge 5'. At a short distance above this edge the wall 5' extends outward, merging into the laterally-extending segmental wall 8. Following the curve of the wall 8 is the curved portion 9, which is cut away on the curve of the cap-wall 5. Across the top 6 is 25 the lip 10, which is connected with the segmental wall 8 by the ends of the curved portion 9 and extends downward at each end along the curve of said portion.

What I claim is—

The design for a gear-case member as herein shown and described.

CHARLES H. METZ.
